Inventor

ROBERT SAYER ASPINWALL,

By Raymond A. Parker

Attorney

UNITED STATES PATENT OFFICE.

ROBERT SAYER ASPINWALL, OF DETROIT, MICHIGAN, ASSIGNOR TO LINCOLN MANUFACTURING COMPANY, OF DETROIT, MICHIGAN, A CORPORATION OF MICHIGAN.

METHOD OF SECURING A NIPPLE TO A HOLLOW SHELL AND ARTICLE PRODUCED THEREBY.

1,382,049.

Specification of Letters Patent. Patented June 21, 1921.

Application filed June 22, 1920. Serial No. 390,983.

To all whom it may concern:

Be it known that I, ROBERT SAYER ASPINWALL, a citizen of the United States, residing at Detroit, county of Wayne, State of Michigan, have invented a certain new and useful Improvement in Methods of Securing a Nipple to a Hollow Shell and Article Produced Thereby, and declare the following to be a full, clear, and exact description of the same, such as will enable others skilled in the art to which it pertains to make and use the same, reference being had to the accompanying drawings, which form a part of this specification.

15 My invention relates to an improved connection between a shell or hollow casing and a nipple carried thereby and my improved process of manufacturing the same.

20 In the drawings, it is shown as a shell adapted to serve as the ball end for a lighting fixture rod or tube provided with a nipple secured thereto with my improved form of connection in such a manner as to prevent rotation of the nipple therein and so as to 25 resist all action tending to loosen the same in the shell.

Figure 1 is an elevation of the completed article.

Fig. 2 is an elevation showing the shell 30 and nipple separated from each other, the shell being cut through on line 2-2 of Fig. 1.

Fig. 3 is a view looking in the direction of the arrow on line 3-3 of Fig. 1.

35 Fig. 4 shows the method of crimping the nipple in position showing one form of punch and die therefor.

Fig. 5 is a section showing the nipple in position secured to the shell.

40 In the securing of a nipple to a shell or hollow casing, the defect in the method followed in the past has been that the connection formed between the nipple and shell has been insecure and the nipple has worked 45 loose under use. This defect has been particularly noticeable in nipples required to support a weight as represented by the nipple carried in the ball end of a lighting fixture bracket and tubes provided with a ball end so provided with a nipple from which is 50 suspended a fixture or lamp.

I provide a metal shell and nipple of conventional design. The shell *a*. is adapted to

be received over the end of a rod or tube, and the nipple *b*. is threaded at one end as at *c*. 55 to receive a fixture or lamp support, and provided with a radial shoulder *d*. adapted to abut the outer surface of the wall of the shell when the nipple is inserted through the aperture formed through the shell wall. 60

A section of the wall of the shell is punched out as shown in Fig. 2, the punched out section of shell wall being forced inwardly in the form of separated tongue like portions *e*. The punching out of a section 65 of shell wall would serve to split the wall section into separated segments forming tongue like portions as shown. A nipple is then inserted through this aperture. The end of the nipple which projects interiorly 70 of the shell is split apart and the split apart sections are forced outwardly so that certain tongue like portions *f*. of the nipple are forced between the separated tongue like 75 portions of the shell and such tongue like portions are laid back against the interior surface of the shell wall as shown in Fig. 3. This interlocking of the sections of the nipple and the shell, and the bending of the same back against the wall of the shell firmly 80 secures the nipple in position so that it will not work loose in any direction.

A preferred method of manufacture would be to punch out the shell as shown in Fig. 2, the tongue like projections being forced 85 inwardly as shown; then insert a nipple in a punch such as *g*. Fig. 4, pass the end of the nipple through the aperture in the wall of the shell, and then by means of a punch or die as *h*. provided with a tapered end adapted 90 to be received within the end of the nipple, and as the punching operation progresses force outwardly the wall of the nipple. This punch is adapted to split the wall of the nipple as it forces its way inwardly. It 95 is here shown as being provided with radial flanges *i*. adapted to force tongue like portions of the nipple outwardly into the interstices formed between the bent back tongue like portions of the shell, and under continuance of pressure force the tongue portions both of the nipple and shell back against the wall of the shell, thereby locking the nipple against rotation relative the shell. The 100 completion of the punch operation would 105 bend back the tongue like projections of the

nipple and shell against the interior surface of the wall of the shell, locking the same firmly in place as the radial flange *d*. forms a support for the shell upon the nipple 5 against which the same may be clenched.

What I claim is:

1. The method of securing a nipple to a shell, which consists in forming an aperture through the wall of the shell by forcing into 10 the interior thereof in split apart portions a section of said wall, inserting a nipple through such aperture, splitting the end of said nipple and bending the split apart portions outwardly so as to interlock between 15 the tongue portions formed from the wall of the shell.

2. The method of securing a nipple to a shell, which consists in punching out a section of the wall of the shell to form an aperture therethrough, the punched out section 20 of shell wall being forced inwardly into the shell in the form of separate tongue like projections, inserting a nipple provided with a radial shoulder through such aperture until 25 the shoulder abuts the shell wall, splitting the end of said nipple and forcing outwardly the split apart tongue like portions of the nipple into the interstices between the tongue like portions of the shell against the 30 shell wall so as to lock the nipple and shell together against said shoulder.

3. The method of securing a nipple to a shell, which consists in forming an aperture through the wall of the shell by punching inwardly 35 a section of the shell wall in the form of separated tongue portions, inserting a nipple provided with a shoulder into such aperture until the shoulder abuts the outer surface of the shell wall, securing such 40 nipple in position by splitting the interiorly projecting end thereof and forcing outwardly tongue like portions thereof into the openings between the tongue like portions of the shell so as to interlock therewith, binding 45 the shell against the shoulder of the nipple.

4. The method of securing a nipple to a shell which consists in forming an aperture through the shell wall by punching inwardly a section thereof in the form of separated 50 split apart tongue like portions, inserting a nipple provided with a radial shoulder through such aperture until the shoulder prevents further entrance of the nipple 55 therein, clenching the end of the nipple outwardly and against the shell wall forcing the shell against the shoulder of the nipple by forcing split apart end portions of the nipple into the openings between the separated tongue like portions of the shell wall 60 locking the nipple and shell together.

5. In an article of manufacture, a shell provided with an aperture through the wall thereof, the section of which shell wall is punched out to form such aperture being 65 broken and bent back inwardly of the shell in the form of separated tongue like portions, a nipple secured to said shell by being passed through said aperture and having split apart end portions thereof bent outwardly interlocking in the interstices between the tongue like portions of the shell wall.

6. In an article of manufacture, a shell through the wall of which an opening has 70 been formed to receive a nipple, the section of shell wall through which the aperture has been made being forced inwardly into the shell in the form of separated tongue like 75 portions laid back radially of the aperture 80 against the interior of the shell wall, a nipple formed with a shoulder adapted to abut the outer surface of said shell wall carried in said aperture the interiorly projecting end of said nipple as regards the shell 85 being split and the split apart sections bent outwardly in such a manner that split apart sections of said nipple dovetail between the tongue like portions of the shell wall.

In testimony whereof, I sign this specification.

ROBERT SAYER ASPINWALL.
